UNITED STATES PATENT OFFICE.

FREDERICK HATHAWAY RAGAN, OF SEATTLE, WASHINGTON.

REVERSING SCREW-AND-NUT GEARING.

1,276,810.

Specification of Letters Patent. Patented Aug. 27, 1918.

Application filed October 13, 1913, Serial No. 795,012. Renewed May 23, 1918. Serial No. 236,231.

To all whom it may concern:

Be it known that I, FREDERICK HATHAWAY RAGAN, a citizen of the United States, and resident of the city of Seattle, in the county 5 of King and State of Washington, have invented certain new and useful Improvements in a Reversing Screw-and-Nut Gearing, of which the following is a full, clear, and exact description.

10 The object of the present invention is to provide an improvement in power devices of the character referred to which will be particularly adapted to supply power to operate automatically the saw shifter of an edging machine used in the manufacture of lumber, which means will be under the complete control of the operator, the action employed in the operation of my power device being identical with that employed in the operation of 15 the present hand device. By the introduction of my invention physical force heretofore relied upon to operate the saw shifter is displaced, therefore increasing the capacity of the mill, and at the same time insuring 20 perfect accuracy.

Having thus indicated the ends sought by me my invention consists in the construction and combination of parts to be more fully described hereafter and particularly set 25 forth in the claims. Reference is to be had to the accompanying drawings forming part of this specification in which similar characters of reference indicate corresponding parts in all the figures.

30 Figure 1 is a perspective view of a standard edging machine with my invention embodied therein.

Fig. 2 is a longitudinal sectional view of my power operating device.

35 Fig. 3 is a sectional view of Fig. 2 cut along the line 2—2, showing the operating device engaging the handle of the saw shifter of the edging machine.

As shown in the drawings the rotary saw 40 X Fig. 1 is moved along the shaft Z by force applied to the operating handle N, which is raised to unmesh from a ratchet under the scale S, which holds the saw in the position desired.

45 It is to be observed that by pulling the lever N, in either direction, guided by the figured scale S, any width of lumber predetermined may be cut. The feed rolls R and R' revolving in the opposite direction feed 50 the lumber against the saw X of which there

are usually from five to eight in number. I have shown but one in the drawings for convenience in description. The rolls R and R' are raised and lowered by air action in the cylinders C and C' to accommodate different 60 thicknesses.

My invention consists of two screw gears, B and B' Fig. 1 and Fig. 2 running the full length of the machine. To the front of each shifter I have bolted or otherwise fastened 65 a small metal case A Fig. 1 through which the screw gears pass. These screw gears are connected with an extension of the lower feed roll shaft by ordinary cog gears G, and so geared together that the screws turn in 70 the opposite direction. It is to be understood that power may be applied to these gears in any way desired, the one essential being that they turn in the opposite directions if the threadings run in the same way.

75 Inclosed within the metal case A Fig. 2 are two round metal nuts M and M' made of any suitable material. In my drawings they are illustrated as having shoulders on each side extending through the side of the case 80 A to admit of more thread bearing than would be possible in a plain nut.

These nuts M and M' ordinarily run free, as they are snugly fitted to the screws B and B' and revolve with them and in opposite 85 directions to each other. The ball bearings D and D' as shown in Fig. 3 are designed to reduce friction with the sides of the case A during this free motion.

The case A is bolted or otherwise attached 90 to the front of the shifter O as shown in Fig. 1. Extending through the upper face of said case A is a forked yoke Y adapted to permit the shifter handle N to rest therein. In place of the ordinary ridged handle such 95 as is used in running the machine by hand I have substituted one which is pivoted at P Figs. 1 and 3.

The yoke Y is pivoted at J and is forked at the bottom to permit of two short lever 100 arms E and E' Fig. 3 to be pivotally extended therefrom. Connected to these arms by suitable rods are two double tipped wedges W and W' Fig. 3.

By operating the shifter handle in the 105 ordinary way by pulling or shoving horizontally which is the identical motion employed when moving the same by hand, pressure is brought to bear upon the yoke Y. If the pressure is exerted to the right 110

of the yoke Y, a lifting movement is imparted to the communicating arms E and E', thereby bringing the wedges W and W' which are attached thereto, into contact 5 with the nut M which is running free with the screw B which is turning in the direction the lever has been previously tilted.

According to the amount of pressure exerted by the operator, these wedges will 10 either entirely stop the free rotary motion of the nut which is turning with the screw or merely slow it up. When the motion of the nut is retarded or stopped the screw will immediately begin to work through it, thereby 15 by carrying the case A along with it and likewise the shifter and saw to which the case is attached. The action is simply reversed by moving the handle N in the opposite direction, which releases the pressure 20 exerted by the wedges upon the nut and the nut resumes its free motion with the screw as before. The wedges have resumed their mutual position between the nuts M and M' until the tilt of the handle N in the 25 opposite direction lowers the arms E and E' and thereby retards or stops the nut on the screw B' by the pressure communicated to it by the wedge as aforesaid described.

30 The bottom screw B' is threaded the same way, but turning in the opposite direction from the screw B carrying the case A and shifter in the opposite direction.

The screws are run in such direction that 35 a pull to the right on the shifter handle N will move the case and the shifter to the right and vice versa. When one nut is wedged and is pulling the shifter in the direction the thread of the screw is revolving, the other nut is pulling against the 40 thread of the screw, thus picking up an extra turn every three or four inches of the thread.

It will be observed that by placing a 45 spring on either side of the forked yoke Y Fig. 2 preferably on top of the case A the wedges W and W' will be automatically centered between the nuts when the handle N is released. It is to be understood that 50 the wedges are made of any suitable material preferably covered with a removable layer of friction material. The nuts likewise may be covered with a layer of friction material.

55 The set screws H Fig. 3 as shown are accessible from the exterior of case A, and can be employed in adjusting the friction surfaces to correct any loss of motion by reason of wear.

60 As can be readily seen the satisfactory action of the apparatus, will depend largely upon the nuts immediately resuming their rotary motion after being freed from the wedges. In event hard usage and wear 65 should render the nuts too loose to act upon

the screw so that adhesion between the screw and nut would not immediately overcome the friction between the side of the nut and the case A, small steel bars or a lug set into the nut from the peripheral 70 surface and bearing upon the thread of the screw actuated by a spring and adjusted by a socket set screw will insure at all times the immediate rotary motion being resumed by the nut upon the releasing of the wedges. 75

The nuts may be turned with either a concave peripheral surface, or with a deep V, which will give more friction surface. However, it is to be understood that other means for applying the friction on the nuts may 80 also be effectively used, viz; compressed air used singly and applied directly to the wedges or other friction producing apparatus by means of arrangement of piston plunger or used in conjunction with an air 85 locking device whereby the action of one or more levers the air will automatically lock the shifter in position after being shut off from the friction wedges or other friction appliances. 90

The friction element employed by my invention is one of the main features, since quarter inch and one-half inch sizes are marked on the scale and used continuously. It is believed that no other method of operating the saws by power can be made delicate enough to allow stopping whenever and wherever desired, and at the same time giving enough power when wanted to move the saws speedily over long distances. 95

The machine is simple and economical in construction; it is capable of increasing the capacity of the mill as it is a well known fact there has not been perfected a power operating device that has withstood the 105 crucial test of accuracy an element which cannot be sacrificed, hence the continual use of physical power to operate the saw shifter in all up-to-date mills where modern inventions have supplanted the old methods in other departments. 110

Having thus described my invention, what I claim is new and desire to protect by Letters Patent is;

1. A device of the class described comprising in combination, screw gears adapted to be continuously rotated, nuts freely carried by said screw gears, oppositely located friction members disposed intermediate said nuts and adapted to bear there against, leverage means connecting said friction members, a casing disposed around said nuts and serving as a support for said leverage means, a handle adapted to engage said leverage means whereby pressure applied to said handle will be transmitted through said leverage means to one of said friction members thereby causing said member to frictionally engage one of said nuts and arrest its free rotative movement with said screw 120 125 130

gear thereby longitudinally shifting said handle in the direction in which pressure is applied.

2. A device of the class described comprising in combination, a pair of screw gears adapted to be continuously rotated, cylindrical nuts carried by said screw gears and adapted to revolve freely therewith, oppositely located friction members disposed 10 intermediate said cylindrical nuts, a casing disposed around said friction members and serving as a support for the same, a lever, links operatively connected to said friction members and having pivot connection with 15 said lever, said lever being pivoted to said casing and having an upwardly projecting arm, a lever having a handle adapted to have contact with said arm, and means whereby said last named lever may retain 20 said friction members in a neutral position out of contact with said cylindrical nuts.

3. A device of the class described comprising in combination, a pair of screw gears adapted to be continuously rotated, cylindrical nuts, freely carried thereby, said 25

screws passing through said nuts, oppositely located vertical friction wedges having convergently inclined faces intermediate said nuts, a casing disposed around said friction wedges and serving as a support therefor and a thrust bearing for said nuts, a lever, upwardly projecting rods rigidly connected to said friction wedges and adapted to be pivotally adjusted to said lever, said lever pivotally attached to said casing and 30 having an upwardly projecting U shaped arm, a lever having a handle adapted to be disposed in said U shaped arm, said casing being provided with a notch in the plane of said U shaped arm whereby the handle of 35 said last named lever may retain said friction wedges in a neutral position out of contact with said cylindrical nuts.

Signed by me at Seattle, Washington, this 4th day of October, 1913.

FREDERICK HATHAWAY RAGAN.
